(57) **CLAIM**

The ornamental design for a segmented clamp, as shown and described.

DESCRIPTION

The subject matter of this design application is related to a utility patent application titled Rotatable Adjustable Segmented Clamp which is being filed concurrently herewith. FIG. 1 is a perspective view of my novel ornamental design; FIG. 2 is a top plan view of FIG. 1 with the bottom being a mirror image thereof;

FIG. 3 is a front side view of FIG. 1 with the rear side view being a mirror image thereof;

FIG. 4 is a side view of FIG. 2 taken along the line 4-4 of FIG. 2 illustrating two segments of FIG. 1 with the other two segments being a mirror image thereof; and,

FIG. 5 is a perspective view of one segment of my novel new ornamental design with top bottom, right side and left side being the same as one of the segments as illustrated in FIGS. 1, 2, 3 and 4.

In the drawings, the broken lines showing a pipe or shaft extending through an abutment surface and the appearance of threads on the bolts as well as the bolts on the design and the threaded opening in FIG. 5 depict unclaimed environmental or functional structure that forms no part of the claim.

1 Claim, 5 Drawing Sheets
